UNITED STATES PATENT OFFICE.

JOSEPH SACHS, OF HARTFORD, CONNECTICUT, ASSIGNOR TO THE JOHNS-PRATT COMPANY, OF HARTFORD, CONNECTICUT, A CORPORATION OF CONNECTICUT.

FUSE-PLUG.

No. 807,781.

Specification of Letters Patent.

Patented Dec. 19, 1905.

Application filed December 19, 1903. Serial No. 185,791.

To all whom it may concern:

Be it known that I, JOSEPH SACHS, a citizen of the United States, residing at Hartford, in the county of Hartford and State of Connecticut, have invented an Improvement 5 in Fuse-Plugs, of which the following is a specification.

My invention relates to fuse-plugs adapted for use in connection with electric cut-out blocks; and the object of my invention is to provide a device of this class in which the fuse wire or strip is inclosed and preferably surrounded by a filling, and therefore free from liability of arcing, and at the same time 15 one in which the fuse after being blown is renewable, if so desired.

In carrying out my invention I employ a casing of metal, preferably cylindrical, a portion of which is screw-threaded, a disk of insulating material secured in the screw-threaded end of the casing, a contact secured centrally in said disk, a cap of insulating material fitting over the opposite end of the casing, means for securing said cap to the casing 20 so that the same is readily removable, a cylinder of insulating material fitting closely within said casing, and electrical and mechanical connections, including a fuse wire or strip between the said casing and the said contact in the disk of insulating material.

In the drawings, Figure 1 is a central vertical section of my improved fuse-plug, and Fig. 2 is a plan of the same. Fig. 3 is a cross-section at line $x-x$, Fig. 1. Fig. 4 is a central vertical section illustrating a modification of the construction shown in Fig. 1 and including a filling material, and Fig. 5 is a plan of the same. Fig. 6 is an inverted sectional plan on line $x'-x'$, Fig. 4. Fig. 7 is a central 35 partial sectional elevation at right angles to that shown in Fig. 1.

a represents the casing or shell of metal of good conductivity, preferably cylindrical, and having a portion thereof provided with 45 screw-threads by which the fuse-plug is received in the cut-out block. The screw-threaded end of the casing a is provided with a disk of insulating material b , in which centrally is secured a button c or other suitable 50 contact device. The opposite end of the shell or casing a is provided with a yoke a' , preferably extending diametrically across the same and integral therewith or electrically connected thereto, and this end of the casing

is also provided with a cap d , of insulating material, into which this end of the casing fits.

As seen in Figs. 1 and 2, the casing a may be provided with fingers or extensions 23 and the cap d with apertures 4 and a recess 60 connecting the same, and the fingers 23 are passed through the apertures 4 and bent down within the said recess in the cap, overlapping one another and secured together by a drop of solder or otherwise, thereby connecting the cap to the case and at the same time making the said parts readily separable, and the recess may then be filled with wax or other suitable insulating material. I also employ a cylinder e or lining of insulating 70 material closely fitting within the casing or shell a and extending between the disk b and the yoke a' . Extending longitudinally within the cylinder e , of insulating material, is a fuse wire or strip f , which is suitably connected at one end to the yoke a' and at the other end in the button or contact c .

As shown in Figs. 4, 5, and 6, I may dispense with the fingers or extensions 23 and employ screws 5, passing through the cap d 80 and extending into the yoke a' , whereby the said cap and shell are securely fastened together. In Fig. 1 I have shown the fuse-strip f connected to fuse-terminals 6; but it will be readily understood that the fuse-terminals may be dispensed with and the ends of the fuse-strips connected electrically in the yoke a' and contact c , respectively, by being soldered therein or otherwise. It is also to be understood that I may employ a filling h , 90 of insulating and non-heat-conducting material, surrounding the fuse-strip f and filling the cylinder e , of insulating material, as shown in Fig. 4.

I claim as my invention—

1. A fuse-plug, comprising a casing having a portion thereof provided with screw-threads, a disk of insulating material secured in the screw-threaded end of the casing, an electrical contact secured centrally in said 100 disk, a yoke integral with and extending across the opposite end of the casing, a cap of insulating material fitting over this end of the casing, means for securing together the said casing and cap in their relation to one another, a fuse-strip within the casing and extending between said yoke and electrical contact, and electrical and mechanical con- 105

nnections between the said fuse and yoke and electrical contact.

2. A fuse-plug comprising a casing having a portion thereof provided with screw-threads, a disk of insulating material secured in the screw-threaded end of the casing, an electrical contact secured centrally in said disk, a yoke in electrical contact with and extending across the opposite end of the casing, a cap of insulating material fitting over this end of the casing and having holes therein, fingers integral with said casing and adapted to extend through the holes in the cap to be turned down thereon to secure the said parts together in relation to one another, a fuse within the casing, and electrical and mechanical connections between the said fuse and yoke and electrical contact.

3. A fuse-plug, comprising a casing having a portion thereof provided with screw-threads, a disk of insulating material secured in the screw-threaded end of the casing, an electrical contact secured centrally in said disk, a yoke in electrical contact with and extending across the opposite end of the casing, a cap of insulating material fitting over this end of the casing, and having holes therein, fingers integral with said casing and adapted to extend through the holes in the cap to be turned down thereon to secure the said parts together in relation to one another, a fuse within the casing, an insulating filling material within said casing and surrounding the said fuse, and electrical and mechanical connections between the said fuse and the said yoke and electrical contact.

4. A fuse-plug, comprising a casing having a portion thereof provided with screw-threads, a disk of insulating material secured in the screw-threaded end of the casing, an

electrical contact secured centrally in said disk, a yoke in electrical contact with and extending across the opposite end of the casing, a cap of insulating material fitting over this end of the casing, and having holes therein, fingers integral with said casing and adapted to extend through the holes in the cap to be turned down thereon to secure the said parts together in relation to one another, a cylinder of insulating material fitting closely within said casing, a fuse within the cylinder, and electrical and mechanical connections between the said fuse and electrical contact. 45

5. A fuse-plug, comprising a casing having a portion thereof provided with screw-threads, a disk of insulating material secured in the screw-threaded end of the casing, an electrical contact secured centrally in said disk, a yoke in electrical contact with and extending across the opposite end of the casing, a cap of insulating material fitting over this end of the casing, and having holes therein, fingers integral with said casing and adapted to extend through the holes in the cap to be turned down thereon to secure the said parts together in relation to one another, a cylinder of insulating material fitting closely within said casing, a fuse within the cylinder, an insulating filling material within said cylinder and surrounding the said fuse, and 60 electrical and mechanical connections between the said fuse and the said yoke and electrical contact. 70

Signed by me this 15th day of December, 1903.

JOSEPH SACHS.
